United States Patent Office.

JOHN McTAGGART, OF ROCHESTER, NEW YORK.

Letters Patent No. 63,410, dated April 2, 1867.

IMPROVEMENT IN GRAIN CLEANERS.

The Schedule referred to in these Letters Patent and making part of the same.

TO ALL WHOM IT MAY CONCERN:

Be it known that I, JOHN McTAGGART, of Rochester, in the county of Monroe, in the State of New York, have invented a new and useful Improvement in Grain Cleaners, designed for ordinary cleaners, but especially applicable to the grain cleaner invented and patented by Gardner E. Throop, and which said patent was dated on the 22d day of December, 1863, and numbered 41,031.

The following is a description of my said invention, reference being had to the accompanying drawing, (which is a copy of Figure 1 of the drawings shown in the said patent of the said Throop, but showing my improvement applied thereto.)

The posts N N, with their cross-pieces, represent the framework, in which the cylinder A is supported. This cylinder A is shown, with a portion of its side removed, at B, for the purpose of exhibiting my improvement, which consists in corrugating the said cylinder circumferentially with small corrugations about the size actually shown in my said drawing. These corrugations add materially to the rigidity, firmness, and durability of the cylinder, and at the same time, by their peculiar form and arrangement with respect to the small perforations, facilitate to a great degree the process of cleaning the grain.

Having thus fully described my improvement, what I claim therein as new, and desire to secure by Letters Patent, is—

The peculiar form and arrangement of corrugations, when combined with the perforations, or their equivalents, substantially as specified.

JOHN McTAGGART.
